HYDRAULIC CALENDER

George C. Munro, Hamilton, Ohio, assignor to
 The Champion Paper and Fibre Company,
 Hamilton, Ohio, a corporation of Ohio

Application March 1, 1939, Serial No. 259,156

3 Claims. (Cl. 92—75)

This invention relates to calender devices and means for exerting, adjusting and controlling the pressure thereon. It has a particular field of utility on paper machines and supercalenders and is especially useful in connection with automatic pressure control mechanism as, and for the purposes described in a copending application, Serial No. 259,154, filed concurrently herewith by Donald B. Bradner and George C. Munro, and entitled "Paper making."

The use of fluid pressure in calender devices, though offering many advantages, has heretofore found little favor in the industry because of the numerous difficulties involved, such as the necessity for a separate pump and accumulator for each calender, and frequently for each side of each calender where it is desired to have different pressures on the two sides, the short life of the usual type of pumping equipment at the high pressures and severe service incident to this use, the lack of adequate controls, etc.

The primary object of the present invention is to provide simple, dependable and durable means for applying and for easily, accurately and continuously controlling the pressure, for adjusting the pressure simultaneously on both sides of the calender, or on one side independently of the other. A further object is to provide means for applying and for independently adjusting fluid pressure on the opposite sides of one calender or a plurality of calenders from a single source of fluid pressure whereby only one of the expensive high duty pumping units will be required, and the costs of installation and maintenance will be brought within practical limits. Other objects will be apparent from the further description of the mechanism involved.

For the accomplishment of these objects I employ, according to the present invention, a novel combination of elements, a novel valve mechanism, and a novel arrangement of controls, in connection with the application of hydraulic pressure to one of the rolls in a single calender or in each of the calenders in a group.

The novel valve mechanism which forms a part of the pressure control devices is advantageously a duplex type of valve which provides a separate control for each side of the calender (each end of the rolls) and which can be adjusted to vary the pressure on the two sides simultaneously or independently, as desired. The valve mechanism is so constructed and arranged as to maintain the pressures for which it is set regardless of variations in thickness of the material passing between the rolls and regardless of variations in the hy-

draulic pressure supply so long as the supply pressure does not fall too low. Each part of the duplex valve mechanism is further preferably arranged to give a reduced and controlled pressure in the fluid supplied to the calender while maintaining the higher pressure in the supply line substantially undiminished.

By the use and proper arrangement of this valve and other elements, as hereinafter more particularly described, I have been able to provide a system for applying any desired pressure to each side of one or more calenders from a single supply of fluid under high pressure under conditions which require extremely small fluid flow and so make it possible to use a durable pump and control without unduly increasing the cost per calender.

The present invention will be better understood by reference to the accompanying drawings, in which one embodiment thereof has been illustrated. In the drawings:

Figure 1 is a front elevation of a supercalender equipped with my hydraulic pressure control devices, in which the fluid circulating system and the pressure control valves are shown diagrammatically and to a distorted scale with parts omitted or displaced for the sake of clarity in the drawing;

Figure 2 is a side elevation of the same calender with a part of one frame broken away;

Figure 3 is a vertical section of the cross head and pressure cylinder, taken on line 3—3 of Figure 2;

Figure 4 is a wiring diagram showing how the pressure control valves may be electrically adjusted;

Figure 5 is an end view of the hydraulic pressure control valve mechanism drawn to a much larger scale, showing the preferred location of the handwheel and pressure adjusting gears, shafts, etc., and showing diagrammatically a power drive mechanism for the adjusting devices;

Figure 6 is a side view of the valve mechanism shown in Fig. 5 with parts broken away to show the construction more clearly;

Figure 7 is a plan view, partly in section taken on line 7—7 of Figure 6, of the same valve mechanism; and

Figure 8 is a fragmentary view showing a modified form of the structures shown in the adjacent portion of Figure 7.

Referring to Figures 1, 2 and 3, a plurality of calender rolls 11, which may be of metal or alternately of metal and other suitable material, are

mounted in frames 13 and 14 which are rigidly held together by tie rods 15. The frames are slotted to form guides wherein the journal boxes 16 are slidably mounted. The lowest of the rolls 11 is journaled in fixed bearings 17 and 18 and the uppermost roll 11 in slidable bearings 19 and 20. In order to increase the calender pressure beyond the weight of the rolls themselves hydraulic cylinders 21 and 22 are mounted on cross heads 23 and 24 at the top of frames 13 and 14, so that hydraulic pressure on pistons 25 and 26 may be transmitted to the journals of the uppermost roll 11 through rods 27 and 28 and bearing blocks 19 and 20.

Fluid, advantageously oil, under pressure is admitted to cylinders 21 and 22 through conduits 31 and 32 respectively which may be provided with strainers 33 and 34 to prevent passage of solid or abrasive material which might damage the pistons or cylinders. The fluid pressure in cylinders 21 and 22 is indicated on gauges 35 and 36 respectively which are connected to conduits 31 and 32, advantageously through pressure snubbers 35—A and 36—A which may be in the form of small orifices and are adapted to prevent damage to the gauges by sudden changes in pressure.

Any fluid which leaks past the pistons 25 and 26 is drained away through conduits 37 and 38 which are joined together in conduit 39 which is free from fluid pressure. Leakage around rods 27 and 28 is prevented by suitable seals or packing rings 40, which, being immediately below drain openings 37 and 38, are practically free from pressure tending to cause leakage.

Fluid under pressure is supplied from any suitable source which may be an accumulator or other means for furnishing fluid at constant pressure. Particularly in cases where a number of calenders are to be served and the amount of fluid required is subject to considerable variation, as more or fewer calenders are used, I prefer the devices illustrated in Figure 1. As there shown, these consist of a supply tank 50 and a suitable pump 51 which may be of a known variable delivery type, driven by a motor 52 and equipped with a known type of control for adjusting the pump discharge as required to give any pressure for which the control devices may be set by means of hand wheel 53. A known type of pressure control valve 55 may also be used. This valve may be adjusted to deliver fluid at a predetermined pressure into pressure main 56 and return excess fluid through pipe 57 to reservoir 50. The valve 55 is adjusted to maintain the hydrostatic pressure in main 56 at or somewhat above the maximum pressure required in cylinders 21 and 22 in order to give the maximum pressure which should be applied to the calender, and serves to maintain this predetermined pressure in the pipe line on both sides of valve 55.

Fluid which is returned from the calender pressure control devices, as hereinafter described, passes into a return main 60, which may, when necessary, be provided with a continuously driven pump 61 to prevent back pressure in the main. This pump delivers the returned fluid, advantageously through a filtering device 62, into pipe 63 which returns the used fluid to supply tank 50.

In order to adjust the calender pressure to the requirements of any particular calendering operation, the pressure in main 56 must be reduced and properly controlled before it is intro-

duced into cylinders 21 and 22 through conduits 31 and 32. For this purpose fluid passes from main 56 through conduit 70 and branch conduits 71 and 72 into pressure control valves 73 and 74 which are adjusted to supply predetermined pressures into conduits 31 and 32, as hereinafter more particularly described, by turning screws 75 and 76 respectively by means of the gears 77 and 78 fixed thereon. The gears 77 and 78 are driven by gears 79 and 80 mounted on shaft 81 which may be turned by a hand wheel 82 which may be provided with a crank handle 82—A as illustrated in Fig. 1, or by a motor as hereinafter described. Gear 78 is turned by gear 80 through an intermediate gear 84 mounted on a stub shaft 83 (see also Figures 5, 6 and 7) supported in a bearing 85 on the body of valve 73. By turning shaft 81 by means of hand wheel 82 (or a motor 150 as hereinafter described) the valves 73 and 74 are simultaneously adjusted to effect a simultaneous adjustment of the pressures in cylinders 21 and 22.

In some cases it may be desirable to have greater pressure on one end of the calender rolls than on the other. If this is desired the structure may be arranged as illustrated in Figure 7 so that by pressing inward on hand wheel 82 gear 79 is displaced along shaft 81, compressing spring 87, and thrown out of mesh with gear 77. Shaft 81 may then be turned and will through gears 80, 84 and 78 turn screw 76 which serves to adjust valve 74 without changing the adjustment of valve 73, thereby securing an independent adjustment of the pressures on the two sides of the calender, when this is required. If independent adjustment is not desired gear 79 may be fixed instead of slidable on shaft 81.

Screws 75 and 76 are threaded into adjusting nuts 91 and 92 respectively which are prevented from turning by feet 95 and 96 respectively which slide on the surface of the bodies of valves 74 and 73. Properly calibrated tension springs 93 and 94 are attached to adjusting nuts 91 and 92, as shown in Figures 6 and 7 so that turning screws 75 or 76 in one direction increases and in the other direction decreases the tension on the corresponding spring. Springs 93 and 94 are attached at their opposite ends by clevises 97 and 98 to levers 101 and 102, which are pivoted at 103 and 104 to the respective valve bodies.

The construction of the valves and the manner in which they function to maintain a predetermined hydrostatic pressure will be best understood by reference to Figure 7, in which valve 74 is shown in section, it being understood that valve 73 is of similar construction. The valves are of the piston type in which piston 111 is accurately fitted into a smooth bore in valve body 74. Piston 111 is provided with a portion 112 of reduced diameter from which a hole 113 communicates with a central bore 114. Conduit 32 which transmits hydrostatic pressure to cylinder 22 opens into the bore in valve 74 at a point which is always in communication with the space surrounding the smaller diameter portion 112 of piston 111. It is thus apparent that the hydrostatic pressure in space 115 at the end of piston 111 will always be the same as that in cylinder 22 which applies pressure to the corresponding side of the calender.

The pressure of the fluid in space 115 on the one end of piston 111 is thus opposed to the pressure applied to the other end of piston 111 by spring 94 acting through lever 102. As long as these pressures are equal, piston 111 will re-

main in the position illustrated in Figure 7, the valve will prevent the passage of any fluid, and the pressure in cylinder 22 and space 115 will remain unchanged. If the spring pressure exceeds the fluid pressure, piston 111 will move to the right until the pressures balance or until the piston reaches the limit of its movement. Movement in this direction brings the reduced diameter 112 opposite the opening of high pressure conduit 72 from pressure main 56 and permits high pressure fluid to pass through the valve into conduit 32 and thence to cylinder 22. When the pressure in cylinder 22 and space 115 reaches the required value, piston 111 is moved back by this pressure to the position shown in Figure 7 and prevents further increase in pressure in cylinder 22.

If, on the other hand, the fluid pressure exceeds the spring pressure, piston 111 will be moved to the left in Figure 7 thus bringing reduced diameter 112 opposite the opening leading into exhaust conduit 120, to permit escape of fluid from cylinder 22 and conduit 32 through the valve into exhaust conduit 120 which leads through conduit 122 into return main 60 and back into supply tank 50. When the pressure in cylinder 22 and space 115 has decreased to the required amount, spring 94 acting through lever 102 moves piston 111 back to the position shown in Figure 7 to prevent further decrease in pressure in cylinder 22.

It may be noted that the movement of pistons 25 and 26 in cylinders 21 and 22 is very small, being equal only to the small thickness of the paper threaded between the rolls, and the slight compression of the non-metallic rolls, when used, under the applied pressure. Consequently only a small amount of fluid need pass through valves 73 and 74 to cause even the maximum required change in pressure, which therefore takes place with corresponding rapidity.

Any fluid which may tend to escape around piston 111 in spite of its accurate fit in the bore of valve body 74 will be caught in annular groove 125 which opens into drain conduit 126 which is free from hydrostatic pressure and which in turn leads through conduit 122 and return main 60 to reservoir 50 or may, if desired, return through a separate drain line to the reservoir in order to avoid any pressure which might exist in exhaust lines 120 and 122. An oil seal or packing ring 128 is also provided to prevent escape of oil during movement of piston 111.

In the operation of calenders it is frequently desirable to quickly release the pressure without disturbing the adjustment. To accomplish a quick release and reapplication of pressure, a handle 131 is provided. This is adapted to rock on shaft 132 from the "on" position illustrated in solid lines to the "off" position indicated by broken lines in Figure 6. Rigidly attached to handle 131 are cams 133 and 134 which when the handle is rocked to the "off" position serve to rock levers 135 and 136 on their pivots 137 and 138 and thereby to press plungers 141 and 142 respectively, as shown in Fig. 6, or to press these plungers directly in a manner which will be evident by reference to Fig. 1. As will be apparent from Figure 7, this movement of plunger 142 moves piston 111 to the left, bringing reduced diameter 112 opposite exhaust opening 120 thereby releasing the pressure in cylinder 22. This will rock lever 102 and extend spring 94, but will not alter the setting of adjusting nut 92 which controls the pressure which will be maintained

in cylinder 22 when handle 131 is returned to the "on" position. Plunger 141 operates in the same manner to open valve 73 and release the pressure in cylinder 21. Leakage around plungers 141 and 142 is prevented by suitable packing glands 143 and 144.

Operation of the valve mechanism by a reversible electric motor 150 may in some cases be preferable to manual operation by hand wheel 82 and crank 82-A as indicated in Figure 1. The motor 150 is advantageously connected through a suitable speed reduction unit 148 to a gear 149 which is arranged to drive gear 11, and will then operate to simultaneously adjust the tension on springs 93 and 94. Depression of hand wheel 82 disengages gear 79 from gear 11 and permits the motor to rotate screw 76 to adjust spring 93 while gear 79, shaft 81, gears 80, 84, and 78, and screw 76 remain stationary and the adjustment of spring 94 consequently remains unchanged.

Operation of motor 150 to adjust the pressure control valves may be controlled as illustrated in Figure 4. Power is advantageously supplied from a three phase line a. h. g., while the operation of the motor and its direction of rotation is controlled by switches 151 and 152 which are closed by energizing coils 153 and 154 respectively. An interlock illustrated diagrammatically at 155 prevents either switch from being closed unless the other is open. The motor is operated in a direction to increase the tension on springs 93 and 94 and consequently the pressure in cylinders 21 and 22 by means of push button 161 which closes a circuit energizing coil 153 thereby closing switch 151. The motor is operated in the other direction to decrease the tension on springs 93 and 94 and the pressure in cylinders 21 and 22 by means of push button 164 which closes a circuit energizing coil 154 thereby closing switch 152. The switches 151 and 152 are normally open switches of convention type held open, when coils 153 and 154 are not energized, by any suitable means such as springs 157 and 158 connected to a common anchorage 159, so that they remain closed and cause the motor to operate only so long as the appropriate push button is depressed. Release of the push button immediately stops operation of the motor and further change in the adjustment.

It is apparent that the adjusting mechanism would be damaged by adjustment too far in either direction. When the adjustment is made manually by turning hand wheel 82 there is little danger of damage due to over adjustment but in the case of electrical adjustment, I prefer to positively prevent over adjustment by the provision of limit switches 165, 166, 167 and 168. These switches are normally closed, but are opened by contact with the feet 95 and 96 on adjusting nuts 91 and 92 when these reach the high or low limits of their respective adjustments (see also Figure 7). Thus when either spring adjusting nut 91 or 92 reaches the low limit of its adjustment the corresponding low limit switch 165 or 166 is opened, breaking the circuit through coil 154, and opening switch 152, thus preventing further adjustment in this direction. Similarly when either adjusting nut 91 or 92 reaches the upper limit of its adjustment the corresponding high limit switch 167 or 168 is opened breaking the circuit through coil 153, and opening switch 151 thus preventing further adjustment in this direction.

In case it should for any reason be desired to

prevent changes in the pressure adjustment while the pressure is turned off and gauges 35 and 36 are at zero and will not indicate the changes, a similar switch 170 may be provided to hold circuits through coils 153 and 154 open while handle 131 is in the "off" position. Switch 170 may be connected for operation by handle 131 in any suitable manner.

In the case of supercalenders, some of the rolls are non-metallic and may be damaged by too great a difference in pressure from one end of the roll to the other. Thus in these cases, though a difference in pressure may be necessary to secure proper calendering action, it may be desirable to prevent the pressure difference from exceeding predetermined limits. While this may be accomplished by relief valves set to operate at the desired maximum pressure differential and inserted between conduits 31 and 32, I prefer a positive mechanical interlock on the adjusting means, as illustrated in Figure 8.

For this purpose gear 77 on screw 15 may be provided with a threaded hub 176 on which is screwed a duplicate gear 177. In place of gear 19 on shaft 81 a wide faced gear 179 is substituted. When gear 179 is pressed inward by hand wheel 82 against spring 87 it is disengaged from gear 77, but remains in mesh with gear 177. Then as gear 77 is rotated by the motor 150, gear 179 remains stationary and holds gear 177 against rotation so that the rotation of gear 77 with its threaded hub 176 causes gear 177 to move along the hub towards or away from gear 77 which limits its motion in one direction, while a collar 178, which may be adjustable if desired, limits its movement in the other direction. To prevent a wedging action of the screw, positive stops 180, 181 and 182 may be provided respectively on gears 77, 177 and collar 178, so that when gear 177 has been moved to the limit in either direction and the engagement of the stops 181 with stops 180 or 182 prevents further turning of threaded hub 176 in gear 177, the teeth of gears 77 and 177 will be in alignment and stops 181 will drive gear 177 along with gear 77 causing gear 179 to rotate the same as if it were in mesh with gear 77. Since when the stops are in contact, the teeth on gears 77 and 177 are in alignment, spring 87 can readily return gear 179 into mesh with gear 77 when pressure on hand wheel 82 is released. It may thus be seen that the amount of movement from its normal position allowed to gear 177, before it contacts gears 77 or collar 178, determines the limits of difference between the pressure adjustments of the two valves, and consequently the maximum pressure differential from one side of the calender to the other.

When the invention is applied to a plurality or system of calenders, each of the several valve mechanisms may be individually adjusted to supply and vary the pressure applied to the corresponding calender and to regulate the relative pressures applied to the two sides of such calender, all without affecting the pressure on any other calender in the connected group. The valve mechanisms quickly and accurately provide pressure changes of small or large magnitude in response to changes in adjustment and in calender pressure, and the volume of fluid flow incident to such pressure changes is very small.

The mechanism as herein described makes possible for the first time a calender system in which fluid pressure can be supplied with little fluid flow to one or a group of calenders from a

single high pressure source of supply, and in which the valve pressures on one or both sides of any calender can be varied at the will of the operator, by small or large increments, without affecting the pressure on any other calenders in the group or on the other side of the same calender.

I claim:

1. In combination, a calender comprising a plurality of rolls, a source of fluid under pressure not less than a predetermined minimum, means for pressing one roll in said calender against another roll therein comprising a pressure cylinder at each end of said roll for receiving fluid under pressure and applying mechanical pressure to the corresponding end of said roll and a conduit for each of said cylinders for connecting said cylinder to said source of fluid under pressure, means for maintaining the pressure between said rolls at a predetermined value comprising a valve in each of said conduits, each of said valves having associated therewith means for exerting a mechanical force, and including balancing means for comparing the fluid pressure in the connected cylinder with said mechanical force, said balancing means responding to conditions of unbalance by movement which admits fluid to said cylinder when the pressure in the cylinder is less than that corresponding to said force and releases fluid from said cylinder when said pressure exceeds that corresponding to said force, means for adjusting the pressure between the rolls in said calender comprising means for simultaneously adjusting by substantially equal amounts the mechanical forces with which the fluid pressures in the cylinders are compared, and means for quickly removing pressure from the calender roll while maintaining the pressure adjustment undisturbed comprising a movable part for simultaneously mechanically moving both of said balancing means in opposition to the forces exerted by said mechanical force exerting means to release fluid from said pressure cylinders.
2. In apparatus of the character described, in combination, a calender comprising a plurality of rolls, a source of fluid under pressure not less than a predetermined minimum, means for applying pressure at each end of a roll in said calender including a hydraulic pressure cylinder associated with each end of said roll, a conduit connecting each of said cylinders with said source of fluid under pressure, means for separately controlling the pressure at each end of said roll comprising a valve housing in each of said conduits having an adjustable spring associated therewith and containing a movable piston balanced between the force exerted thereon by the fluid pressure in the associated cylinder and a mechanical force exerted thereon by said spring, said piston acting when said forces are in balance to prevent pressure fluid from entering or leaving the associated pressure cylinder and when said forces are out of balance to admit pressure fluid to said cylinder if the force exerted by said spring overbalances that exerted by the fluid and to permit escape of pressure fluid from said cylinder if the force exerted by said spring is overbalanced by that exerted by the fluid, separate means for adjusting the pressure maintained by said control means at the opposite ends of said roll, each of said adjusting means comprising screw means for adjusting the force exerted by said spring on the corresponding piston, and means for providing either independ-

ent or simultaneous and substantially equal adjustment of the pressure exerted at opposite ends of the roll comprising a separable driving connection between said screw means whereby operation of one may also operate the other.

3. In apparatus of the character described, in combination, a calender comprising a plurality of rolls, a source of fluid under pressure not less than a predetermined minimum, means for applying pressure at each end of a roll in said calender including a hydraulic pressure cylinder associated with each end of said roll, a conduit connecting each of said cylinders with said source of fluid under pressure, means for separately controlling the pressure at each end of said roll comprising a valve housing in each of said conduits having an adjustable spring associated therewith and containing a movable piston balanced between the force exerted thereon by the fluid pressure in the associated cylinder and a mechanical force exerted thereon by said spring, said piston acting when said forces are in balance to prevent pressure fluid from entering or leaving the associated pressure cylinder and when said forces are out of balance to admit pressure fluid to said cylinder if the force

- exerted by said spring overbalances that exerted by the fluid and to permit escape of pressure fluid from said cylinder if the force exerted by said spring is overbalanced by that exerted by the fluid, separate means for adjusting the pressure maintained by said control means at the opposite ends of said roll, each of said adjusting means comprising screw means for adjusting the force exerted by said spring on the corresponding piston, means for providing either independent or simultaneous and substantially equal adjustment of the pressures exerted on opposite ends of said roll comprising a separable driving connection between said screw means whereby operation of one may also operate the other, and means for preventing the pressure at one end of said roll from being adjusted to differ by more than a predetermined amount from that at the other end thereof comprising means for re-establishing said driving connection when one of said screw means has been adjusted to cause the force exerted by one of said springs to differ by more than a predetermined amount from that exerted by the other spring.
